(57) **CLAIM**

The ornamental design for a connection component, as shown and described.

DESCRIPTION

FIG. 1 is a front perspective view of a connection component showing our new design;

FIG. 2 is a front elevation view thereof;

FIG. 3 is a rear elevation view thereof;

FIG. 4 is a right elevation view thereof, a left elevation view being identical thereto;

FIG. 5 is a top plan view thereof, a bottom plan view being identical thereto; and,

FIG. 6 is a cross-sectional view thereof taken along the line 6-6 in FIG. 4.

The diagonal broken lines in FIG. 6 indicate solid portions of the article intersected by the projected line 6-6.
